UNITED STATES PATENT OFFICE.

WILLIAM M. SCOTT, OF TREDYFFRIN TOWNSHIP, CHESTER COUNTY, PENNSYLVANIA.

SWITCH-HOUSING STRUCTURE.

Application filed December 19, 1923. Serial No. 681,657.

My invention relates to structure for housing switches, circuit breakers and the like utilized for controlling circuits carrying current for lighting, power, or any other purpose.

In accordance with my invention the circuit breaker or switching mechanism is carried upon a base which is carried by or forms a wall of a housing within which are made the connections between the terminals of the circuit breaker or switch mechanism and the supply and consumption circuit terminals, the housing having one or more wall portions or panels movable or removable to permit access to the connections, each wall portion or a panel being held or locked against movement or removal as by a second housing enclosing the circuit breaker or switch mechanism.

Further in accordance with my invention there are provided novel means carried by and operable from the exterior of the housing which encloses the circuit breaker or switching mechanism for manually actuating and tripping the circuit breaker and switching mechanism.

My invention resides in features of structure and combination hereinafter described and claimed.

For an illustration of one of various forms my invention may take, reference is to be had to the accompanying drawings, in which:

Fig. 1 is a side elevational view, partly in vertical section, of apparatus embodying my invention.

Fig. 2 is a fragmentary horizontal sectional view, partly in plan, taken on the line 2-2 of Fig. 1.

Fig. 3 is a side elevational view of the rear housing, with its panels removed.

Fig. 4 is a front elevational view of the structure shown in Fig. 3.

Figs. 5, 6 and 7 are plan, side and end elevations, respectively, of one of the removable panels.

Fig. 8 is a fragmentary front elevational view of part of the actuating or controlling mechanism.

Referring to the drawings, upon a base 1, preferably of insulating material, is secured the switching mechanism which, in the example illustrated, comprises two similar automatic circuit breakers, disposed in series with each other in the circuit and thereby constituting a so called "double arm" circuit

breaker, the two arms or poles of which are independently operable to normal or circuit closing position, with automatic tripping mechanism ensuring the tripping of the arm 60 or pole first closed if there obtains an overload or other abnormal electrical condition upon attempt to close the other arm or pole, in general the same as described in my prior Patent Number 1,389,996. 65

Inasmuch as the two arms or poles are similar in structure, a description of one will suffice for both.

Each arm or circuit breaker comprises the main terminals 2 and 3 adapted to be 70 bridged by the laminated contact member 4 carried by an arm 5 pivoted at 6 to the bracket or support 7 secured to the base 1.

Associated with the upper main terminals 2 are the metallic and carbon stationary 75 shunt contacts 8 and 9, respectively, with which co-act, respectively, the movable metallic and carbon shunt contacts 10 and 11. Pivoted to the arm 5 at 12 is a toggle link 13 pivoted at 14 to the second toggle link 80 15, pivoted to the bracket 7 at 16 and having the forwardly extending portion of lever arm 17 carrying at 18 a pin or roller with which engages the latch 19 pivoted at 20, the latch 19 when in engagement with the 85 pin or roller 18 locking the parts in circuit closing position indicated. Pivoted at 20 is the latch actuator 21 adapted to strike the upper side of the latch 19 to trip the circuit breaker when the tail 22 of the latch 90 actuator is engaged by the armature 23, pivoted at 24, of an electromagnet comprising a U shaped iron magnet core or yoke 25 embracing the downwardly extending portion 26 of the main terminal 3. Secured to 95 the lever arm 17 is the downwardly or forwardly extending arm 27, upon which is pivoted at 28 the roller 29. Secured to the arm 27 is the bracket or arm 30 carrying the visual signal or indicating member 31 100 suitably disposed with respect to an aperture in the enclosing housing wall W.

Upon the front wall W, which may be pivoted or fixedly secured to the housing H, is the bracket 32 providing a bearing for 105 the rotatable shaft 33 upon whose inner end is secured the actuator 34 having the laterally extending actuating arms or cams 35 adapted at their portions 36 to engage the rollers 29 and thereby actuate in succession 110 the lever arms 27 of the two breakers to effect their movement to circuit closing and locked

position successively. The member 34 is provided with lug structure 34^a with which co-acts a torsion spring, not shown, which co-acts also with the lug 32^a, on bracket 32, whereby the actuator structure 34 and the other parts secured to the shaft 33 are returned to normal or neutral position indicated.

Movable longitudinally in the bore 37 of the shaft 33 is the rod or plunger 38 having at its outer end the knob or push button 39 and at its inner end the head 40 adapted to engage and actuate upon inward movement of the plunger 38, the arm 41 of a tripping member 42 pivoted to the bracket 32 at 43 and having a tail 44 extending beyond the pivot 43 and having attached thereto one end of the spring 45, whose other end is attached at 46 to the bracket 32, the spring 45 biasing the member 42 against rotation in counter-clock-wise direction as effected by the plunger 38. The tripping member 42 has a third arm 47 disposed adjacent the outer end 48 of an arm or lever 49 secured to the transversely extending bar 50, secured at its opposite end to the latch actuators 21 of the two circuit breakers, the bar 50 being actuated in response to inward movement of the plunger 38 to actuate the latch actuators 21 and therethrough the latches 19, of both circuit breakers, to trip them. Upon attraction of the armature 23 of either circuit breaker the bar 50 is actuated to effect tripping of the other circuit breaker.

Secured to the shaft 33, on the exterior of the wall W, is the operator's handle or lever mechanism 51, 51, for actuating the actuator members 35, 35, to re-set the circuit breakers in succession. Carried by one of the members 51 is the member 52 in which is slidably a latching plate or bar 53 for engagement in an aperture in the wall W to prevent movement of the operator's levers 51, 51 when there is applied in the notch 54 the hasp of a padlock the insertion of which forces the locking plate 53, toward the left, to engage in the aperture in the wall W, a spring, not shown, withdrawing the locking member 53 upon removal of the padlock.

Locking structure of this character is disclosed in my prior application Serial Number 655,196, filed August 2, 1923.

The rear housing R is secured by any suitable means, as screws 55, to any suitable fixed support, as a wall, post or the like. At the forward end of its top, it is provided with two pivot pins or equivalent, with which engage pivot hooks 57 secured to the base 1 by screws 58, whereby the base 1 and the mechanism carried thereby may be swung upon the pivot pins 56. During normal operation however, the base 1 is secured in the position indicated in Fig. 1 by screws 59 threaded into suitable members carried by the rear housing R.

The housing H has secured thereto at the rear edge of its top the two pivot hooks 60 by which the housing H and the parts carried thereby are pivoted or hinged upon the members 56 carried by the housing R.

The housing H is held in the position indicated in Fig. 1 by means of holding structure comprising the brackets 61 secured to the bottom wall of the housing R and having pivoted therein the bail or hasp 62 which engages in the slot 63 in the link 64 pivoted at 65 upon the bracket 66 secured to the housing H. The members 62 and 64 comprise, in effect, links of a toggle which in the position indicated in Fig. 1 are in over-travelled position in the sense that in moving the links to the position shown the center of pivot 65 has been traversed and lies to one side of the imaginary line joining the center of the pivot of the member 62 with the point of engagement of member 62 with the link 64. The toggle being so over-travelled remains in the position indicated holding the housing H and the parts carried thereby in fixed position with respect to the housing R and base 1. The link 64 at its forward end has a hole 67, which is adapted to register with the hole 68 in the bracket 69 secured to the housing H, whereby the locking member, as the hasp of a padlock, may be passed through the registering holes 67 and 68 to prevent rotation of the link 64 in clock-wise direction about its pivot 65 to release the housing H from the housing R.

Secured to the upper terminal blocks 2 and extending through the base 1 into the rear housing R, are the connecting studs 70 on which are threaded nuts 71 between which are clamped the terminals 72 at the ends of the supply (or consumption) circuit conductors 73 disposed within a pipe or conduit 74 communicating with the interior of the housing R.

Similarly the studs 74 connect with the lower ends 74^a of the main terminal block 3 and extend through the base 1 into the housing R where they carry nuts 75 between which are held the terminals 76 on the ends of the consumption (or supply) circuit conductors 77 disposed in the pipe or conduit 78 communicating with the interior of the housing R.

The rear wall of the housing R is composed mainly of the plate 79, having the forwardly bent vertical side members 80. The top and bottom walls 81 and 82 of the housing R have downwardly and upwardly turned flanges 83 and 84, respectively, riveted to the forwardly extending plates 85 and 86 integral with the rear plates 87 and 88 which are bent downwardly and upwardly from and integral with plates 81 and 82 respectively. The plates 85 and 86 are riveted to the side members 80 of the plate 79, and the rear plates 87 and 88 are riveted

to the rear plate 79. The plates 86 carry the members 86^a, Figs. 1 and 4, into which are threaded the aforesaid screws 59. The structure thus far described is in effect a portion or skeleton of the rear housing R, which is completed by application thereto of the panels or movable or removable wall portions 89 each of which has at its front edge the flange 90 parallel with and outside of the rear housing plate 79. Struck up from each panel 89 is a plurality of lugs 91 integral with and suitably spaced from the plane of the plate 89 by the member 92. The plates 85 and 86 are provided with apertures 93 through which the lugs 91 are passed so that they lie on the inner sides of the plates 85 and 86 whereupon each panel 89 may be slid toward the rear, as viewed in Fig. 1, carrying the free ends of the lugs 91 past and to the left of the left ends of the apertures 93, thereby holding the panels 89 in place. With the parts in assembled and normal position indicated in Fig. 1, the flange or abutment 90, upon the panel 89, is disposed adjacent or against the flange or abutment 94 on each rear vertical edge of the housing H, as indicated in Fig. 2. It will be noted that the base 1 is preferably narrower than the space between the abutments 90 and 94 on opposite sides of the housing structure, as indicated in Fig. 2, so affording space for free movement of the housing H and the panels 89 and their abutments 90 and 94.

When it is desired to have access to the interior of the housing R, to the studs, conductors, terminals or connections therein, the toggle link 64 is first rotated in clockwise direction and the bail 62 detached therefrom, whereupon the housing H may be swung or rotated upon the pivot pins 56, in counter-clockwise direction, as viewed in Fig. 1, thereby carrying the rear edge of the housing H toward the right, and removing the flanges or abutments 94 away from the flanges or abutments 90 upon the panels 89, whereupon either or both of them may be slid, toward the right, until the lugs 91 come again into register with the openings 93 in the plates 85 and 86, whereupon either or both of the panels may be removed, allowing ready access to the interior of the housing R to make connections or to effect disconnection of the conductors 73 and 77, or any of them from the circuit breaker studs.

By recourse to structure of the character described, involving one or more panels 89, it is not necessary to provide or allow for slack in the conductors, since the base 1 may remain in fixed position with respect to the rear housing R and the short direct connections indicated may be made.

What I claim is:

1. The combination with a base, of switching mechanism disposed thereon and a

housing attached to said base, conductors extending from said switching mechanism through said base into said housing, circuit conductors extending into said housing for connection with said first named conductors, 70 a member constituting a portion of the wall structure of said housing, and means for detachably securing said member upon said housing, comprising apertures and lugs extending therethrough, whereby said member 75 may be moved laterally of a wall of said housing and then parallel therewith to effect attachment and detachment of said member.

2. The combination with a base of switching mechanism disposed thereon, a housing attached to said base, said base terminating short of one side of said housing to form a space, a member constituting a portion of the wall structure of said housing slideable upon and detachably secured to said side of said housing, an inwardly turned abutment on said member movable in said space, and structure co-acting with said abutment for preventing detaching movement of said member.

3. The combination with a base, of switching mechanism disposed thereon, a housing attached to said base, said base terminating short of one side of said housing to form a space, a member constituting a portion of the wall structure of said housing slideable upon and detachably secured to said side of said housing, an abutment on said member movable in said space, and a second abutment movable in said space in the path of said first named abutment for preventing detaching movement of said member.

4. The combination with a base of switching mechanism disposed thereon, a housing attached to said base, said base terminating short of one side of said housing to form a space, a member constituting a portion of the wall structure of said housing slideable upon and detachably secured to said side of said housing, an abutment on said member, a second housing enclosing said switching mechanism, and having an in-turned abutment movable in said space in the path of said first named abutment for preventing detaching movement of said member.

5. The combination with a base, of switching mechanism thereon, a movable housing enclosing said switching mechanism, a second housing, circuit conductors extending into said second housing for connection to said switching mechanism, and a removable wall, which upon removal allows access to said second housing, held in housing-closing position thereon by said movable housing.

6. The combination with a base, of switching mechanism thereon, a movable housing enclosing said switching mechanism, a second housing, circuit conductors

extending into said second housing for connection to said switching mechanism, and a removable wall, which upon removal allows access to said second housing, held in housing-closing position thereon by direct engagement with said movable housing.

7. The combination with a base, of switching mechanism thereon, a movable housing enclosing said switching mechanism, a second housing, circuit conductors extending into said second housing for connection to said switching mechanism, and a removable wall comprising an abutment, which upon removal allows access to said second housing, held in housing-closing position thereon by engagement of said abutment with said movable housing.

8. The combination with a housing, of a base attached thereto, switching mechanism carried upon said base outside of said housing, a second housing pivoted upon said first named housing and enclosing said switching mechanism, a member constitut-

ing a portion of the wall structure of said first named housing detachably movable thereon to permit access to the interior of said first named housing, said second housing preventing movement of said member until said second named housing is rotated upon said first named housing.

9. The combination with a base, of switching mechanism thereon, and a housing attached to said base, said housing comprising a wall member spaced from said base and having side portions turned toward said base, end wall structure for said housing comprising an end wall member having portions extending parallel with and secured to said first named wall member and said side portions thereof, and a panel member detachably secured to the portion of said end wall member which is parallel with and secured to one of said side portions of said first named wall member.

WILLIAM M. SCOTT.
